(57) **CLAIM**

The ornamental design for an alignment sleeve for eye-drop bottle, as shown and described.

DESCRIPTION

FIG. 1 is right side isometric view of an alignment sleeve for eye-drop bottle showing my new design;

FIG. 2 is a right side elevational view thereof, the left side elevational view being a mirror image thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a side cross-sectional view taken along line 7-7 of FIG. 3.

The broken line showing of the eye-drop bottle in FIG. 7 depicts environmental structure and forms no part of the claimed design.
